UNITED STATES PATENT OFFICE.

DAVID KARGER, OF MILWAUKEE, WISCONSIN.

CAP.

Application filed June 7, 1923. Serial No. 643,996.

My invention relates to caps, more particularly knitted caps, and is concerned with that type of cap wherein protecting portions for the back of the neck and the ears of the wearer are provided and wherein such protecting portions may be placed in and out of use.

My invention contemplates an improved structure whereby different knit stitches may be employed respectively for different parts. By the use of my invention uniformity of formation may obtain notwithstanding the use of different knit stitches for different parts, as distinguished from peculiar or particular formation for each kind of knit stitch or combinations of stitches. Thus a manufacturer may maintain a uniform style or design and yet offer, in such style or design, a variety of knit stitches or combinations of stitches.

In the drawings:

Figure 1 is one side elevational view, showing the neck and ear protecting portions in the out-of-use position;

Figure 2 is the opposite side elevational view, showing the neck and ear protecting portions in the in-use position; and

Figure 3 is a rear elevational view showing the out-of-use positions of the neck and ear protecting portions in full lines and their in-use positions in dotted lines.

The cap of my invention comprises primarily a hemi-spherical knitted crown *a*.

Appended to the lower margin *b* of the crown *a* is a band *c* which extends around the back of the crown and forwardly to a point beyond the center, so that when in its upper or non-use position, folded against the crown, it appears as in Figure 1, and when in its lowered or in-use position, pending downwardly, it appears as in Figure 2, so that it will then encircle the back of the neck of the wearer and will extend forwardly to a point forward of the ears of the wearer.

Joined to the free ends of the band *c*, on the oblique lines *d*, *d'*, respectively, which lie approximately 45° to the crown margin *b*, are the flaps *e*, *e'*, respectively, the long axes of the flaps lying approximately at right angles to the long axis of the band. When

these flaps are in their upper or non-use position, folded against the crown, they appear as in Figure 1, and when in their lowered or in-use position, pending downwardly, they appear as in Figure 2, so that they form ear muffs for the wearer.

The flaps *e*, *e'* are held in their upper position, and with them the band *c*, by means of buttons *f*, *f'* respectively, sewed onto the crown in the position shown, and passing through button holes *g*, *g'* respectively, properly disposed in the respective flaps. The flap *e'* has a button *h* sewed on the inner (when in raised position) side thereof, near the end, and this button passes through the buttonhole *g* in the flap *e* when the flaps are in the lowered position, as shown in Figure 2 and in dotted lines in Figure 3. Thus are the ends of the flaps joined together below the chin of the wearer. When the flap *e'* is in its raised position, this button *h* is hidden behind it.

The band *c*, from point *j* to point *k* is of uniform width. It is preferably made of a stitch which lends itself to stretch in width, while the flaps are preferably made of firmer knit. It will be noted that by the formation described the downward and forward pull of the flaps, when joined below the chin of the wearer, is through an intervening triangular portion, so that when the band, or at least the triangular portion thereof, is made of a stitch which will lend itself thereto, this pull will be accommodated without requiring the flaps themselves to do so or pulling the crown out of shape.

The cap illustrated is a specific embodiment of my invention to which the appended claims are more or less broadly or specifically drawn. By actual manufacture, I have demonstrated that the band *c* may be of plain, rack or half cartigan knit, and the flaps *e*, *e'* may be of plain rack or half cartigan knit or any combination may be employed, or even portions of either may be variously knitted without departing from the formation I have described.

I claim:

1. A knitted cap comprising a substantially hemi-spherical crown, a portion of one

100

kind of knit appended to the lower margin thereof in the region of the ears, and flaps of another kind of knit appended from said portion on a line oblique to said margin.

5 2. A knitted cap comprising a substantially hemi-spherical crown, a portion of one kind of knit appended to the lower margin

thereof in the region of the ears, flaps of another kind of knit appended from said portion on a line oblique to said margin, and 10 a neck portion joining said portions.

In witness whereof, I hereunto subscribe my name this 5th day of June, 1923.

DAVID KARGER.
